ASSIGNORS TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,324,216.

Specification of Letters Patent.

Patented Dec. 9, 1919.

Application filed November 1, 1917. Serial No. 199,653.

To all whom it may concern:-

Be it known that we, HARRY H. STYLL and LUCIAN W. BUGBEE, citizens of the United States, residing at Southbridge, in the county of Worcester and State of Massachusetts, have invented certain new and useful Improvements in Ophthalmic Mountings, of which the following is a specification.

10 This invention relates to improvements in ophthalmic mountings and has particular reference to improved means for satisfactorily connecting the metallic parts or fittings of such mountings to lenses in a firm and secure manner.

One of the leading objects of the present invention is the provision in connection with a slotted lens of novel and improved means for securely engaging with the slot to properly connect the lens and fitting.

20 A further object of the present invention is the provision of an improved construction of lens clip in which spreading and expansion of the strap ears or lens engaging members is prevented and in which mechanical means are provided within the clip to interlock with the lens and secure it in place.

25 A further object of the present invention is the provision of an improved construction 30 of mounting for use in connection with a slot and cement joint between the mounting and lens, which will possess the various advantages present in previously known slot and cement constructions so far as rigidity 35 of the clip ears and interlocking of the parts is concerned and which will in addition possess certain supplemental mechanical locking devices for securely engaging and connecting the parts should the cement fail 40 to properly secure them.

Other objects and advantages of our improved construction should be readily apparent by reference to the following specification taken in connection with the accompanying drawings, and it will be understood 45 that we may make any modifications in the specific details of construction shown and described within the scope of the appended claims without departing from or exceeding 50 the spirit of our invention.

Figure I is a front elevation of a pair of eyeglasses provided with our improved mounting.

Fig. II is an enlarged elevation of one

lens, one ear of the strap being removed to show how the strap is secured to the lens.

Fig. III is a view similar to Fig. II illustrating a modified form of fastener.

Fig. IV is a view similar to Fig. III illustrating still another form of the invention.

Fig. V is a transverse sectional view through the fastener and lens strap.

Fig. VI is a sectional view similar to Fig. IV illustrating another form of the invention.

In carrying out our invention we first provide a lens 1 having a slot 2 which extends longitudinally from the edge of the lens and opens into a transverse opening 3 disposed adjacent the edge of the lens and adapted to receive the fastening member carried by the lens strap. The lens strap 4 which includes the side ears 5 may be of a simple construction as shown and provided with a transverse central portion 6 having 70 extending inwardly therefrom the spaced parallel spring members 7 the outer ends of which are curved in opposite directions as shown at 8 so that after they have been passed into the opening the tension of the 80 springs will project the curved portions 8 into the opening 3 and retain the arms or members 7 against withdrawal from the opening 3.

It will be apparent from the foregoing 85 that a lens could be quickly and readily attached to a temple side or nose piece by the insertion of the spring arms 7 into the slot 2 and then into the opening 3. In order to securely retain the spring arms against withdrawal from the opening 3 and slot 2 these 90 openings are filled with a cement that will entirely fill the space between the two strap ears 5 and when hardened will positively prevent any lateral or longitudinal movement of the members embedded within the cement.

In Fig. III we have illustrated a modified form of the invention which includes, in addition to the spring arms 7, a transverse movable web 9 the ends of which are rotatably mounted in the strap ears 5 as shown at 10 whereby when the strap is being applied to the lens the web is arranged in a substantially horizontal plane with respect to the straps 5 so that it can be readily passed through the slot 2 into the opening 3 with the spring arms 7. After the web

and curved ends 8 of the spring arms are arranged in the openings 3 the web is rotated in its bearings 10 until the same is disposed in a substantially transverse position with respect to the arms, the rotation of the web 9 engaging its longitudinal edges with the curved portions of the arms 7 and forcing them apart and retaining them in this position whereby any liability 5 of withdrawal from the opening is entirely eliminated. In order to securely retain the web 9 and arms 7 in their operative positions the opening 3 and slot 2 are filled up with cement so that all space around the 10 web and arms is entirely filled thus retaining these members against movement. From this it will be apparent that the arms 7 will be forced apart into a further open position by the use of the web 9 so as to 15 positively retain these two members in their operative positions.

In the formation of the lens mount it is preferred to have the arms 7 made from a single piece of material bent into U shaped 20 form and having its intermediate portion soldered or otherwise secured to the central portion of the strap midway of the two ears 5. The width of these arms is substantially the same as the space between the 25 two straps only a small space being left between the longitudinal edges of the arms and the inner walls of the straps. It will be understood that while we have shown and described the arms 7 as soldered or 30 otherwise secured to the lens strap it will be readily understood that these arms may be integrally formed with the strap.

In applying our improved strap to the lens the slot 2 and opening 3 are first filled 35 with cement and then the web 9 turned so that it lies in a horizontal plane with respect to the ears 5 and the spring arms 7 are pressed together so that they may be readily inserted into the slot 2 and pushed 40 inwardly until the curved portions 8 reach the opening 3 where the tension of the spring will force these curved portions into the opening. The curved portions are then secured in place by turning of the web 9 into 45 a transverse position thus spreading the curved portions apart to retain them within the opening 3 and as the cement hardens the arms and web will be rigidly held in their respective positions. It will be understood 50 however that these arms and web may be readily used without the cement as they will hold the strap in place through the engagement of the curved portions of the arms with the side walls of the opening 3. In 55 Fig. III we have illustrated the mounting part in elevation and part in section showing how the arms 7 will contact with the opening and also with the sharp edge 11 to securely hold the strap on the lens.

60 In Fig. IV we have illustrated another

modified form of the invention wherein the fastening means is so constructed that the strap may be quickly and readily removed from the lens or attached thereto. In this form of the invention the curved portions 70 of the arms 7 are formed with indentations as shown at 12 adapted to receive the longitudinal edges of the web 9 when disposed in a transverse position so as to securely lock the web and arms in the respective positions 75 and retain the strap in engagement with the lens. It will be noted however that the web can be readily unlocked from between the arms by turning the same against the tension of the spring arms. From this it will 80 be apparent that as soon as the spring arms are inserted into the opening 3 the web 9 is turned and engaged with the indentations whereby the curved portions will be securely held within the opening 3.

85 In Fig. VI, we have illustrated another form of the invention wherein the spring arms 7' are secured at their intermediate portions to the inner end of a block 13 which is carried by the strap 4. This block 90 may be integrally formed with the strap or of a separate piece and secured to the same in any suitable manner. However, this block extends into the recess 2 of the lens and any suitable means may be used 95 to connect the intermediate portion of the spring members 7' to the inner end of this block.

The form of construction illustrated in Fig. VI possesses a particular advantage 100 which is present, though to a less pronounced degree, in connection with the forms illustrated as well in Figs. II, III and IV, this advantage residing in the fact that by our improved construction the two lens 105 clip ears 5 are held in predetermined spaced relation, as by the block or portion 13, and are prevented from either contraction or crushing against the lens or from expansion or spreading away from the lens, this being 110 accomplished in Figs. III to V through the interlocking of the spun over or flared portion 14 and head 10 of the locking member 9, which parts serve to hold the ears against expansion, while the width of the member 115 9 is such as to prevent their contraction, and being accomplished in Fig. VI in addition by the presence of the solid block 13 between the inner portions of the clip ears, it being understood that in this event the block 13 is 120 of approximately the size to fit the recess but preferably allowing a slight amount of cement to fit around the block and unite the edges of the slot in the lenses with the block, while the spring fingers at the outer end 125 spread outward into the enlarged or circular recess in the lens in such a manner that the block fits the lens and prevents play of the lens while the fingers spread out into the aperture and hold the lens on the block, even 130

in the absence of the cement or the locking member 9, while in the presence of both these members the locking member 9 spreads the fingers out to more securely lock them in position and the cement fills the cavity, binds the parts together and tends to hold the spring fingers in expanded locking position and thus secures most efficient results in both cementitiously and mechanically securely connecting the lens and fitting, and preventing any accidental loosening or separation of the parts.

We claim:

1. A lens mounting including a lens having a slot extending in from its peripheral edge and communicating with an opening in the lens, a lens strap, a pair of spring arms carried by the strap for engagement with the slot and opening, and means carried by the strap for engagement with the arms to force them apart in the opening.
2. A lens mounting including a lens having a slot extending in from its peripheral edge and communicating with an opening in the lens, a lens strap, a pair of spring arms carried by the strap for engagement within the slot, oppositely curved portions formed on the inner ends of said arms for engagement within the opening and means carried by the strap for engagement with the curved arms to force them apart in the opening.

3. A lens mounting including a lens having a slot extending in from its peripheral edge and communicating with an opening in the lens, a lens strap, a pair of spring arms carried by the strap for engagement within the slot, oppositely curved portions formed on the inner ends of said arms for engagement within the opening, said curved portions having indentations formed therein and a movable web carried by the strap and adapted to have its longitudinal edges in engagement with the indentations as and for the purpose set forth.

4. A lens mounting including a lens having a slot extending in from its peripheral edge and communicating with an opening in the lens, a lens strap, a pair of spring arms carried by the strap for engagement within the slot and opening, oppositely curved portions formed on the inner ends of said arms for engagement within the opening and a movable web carried by the straps for engagement with the curved portions to force them apart into engagement with the walls of the opening.

In testimony whereof we have affixed our signatures in presence of two witnesses.

HARRY H. STYLL.
LUCIAN W. BUGBEE.
